SPECIFICATION forming part of Design No. 31,348, dated August 8, 1899.

Application filed January 6, 1899. Serial No. 701,406. Term of patent 14 years.

To all whom it may concern:

Be it known that I, EDWARD A. The drawing shows in elevation a handle with my design appearing thereon.

The characteristic features of my design are the peculiar fanciful figures 1 1, located at a

distance apart from each other on the surface 15 of the handle 2, the divergent portions of the said figures facing each other.

I claim as my invention—

In testimony whereof I affix my signature in presence of two witnesses.

EDWARD A. HEWITSON.
